No. 892,174.

PATENTED JUNE 30, 1908.

M. MAYER.
CORD HOLDER.
APPLICATION FILED MAY 1, 1908.

UNITED STATES PATENT OFFICE.

MORITZ MAYER, OF NEW YORK, N. Y.

CORD-HOLDER.

No. 892,174.

Specification of Letters Patent.

Patented June 30, 1908.

Application filed May 1, 1908. Serial No. 430,282.

To all whom it may concern:

Be it known that I, MORITZ MAYER, a citizen of the United States, residing at the borough of Manhattan, city, county, and State 5 of New York, have invented an Improvement in Cord-Holders, of which the following is a specification.

The present invention relates to a receptacle for holding balls of cord and like articles and from which the cord or string may be drawn for use in wrapping parcels or for various other purposes; the object of my invention being the provision of a simple and ornamental cord holder which is collapsible 15 not only for the purpose of readily placing a ball of cord therein but also for convenience and for effecting a saving in the expense of packing and shipping.

In carrying out my invention I preferably 20 employ a base or bottom member, a series of side members arranged in pairs, the parts of each pair being hinged together and one of said parts hinged to an edge of the bottom or base member, and means for supporting or 25 suspending the holder, as will be hereinafter described.

In the drawing, Figure 1 is a plan view of my improved cord holder with the parts shown in their collapsed position. Fig. 2 is 30 a sectional elevation on line x, x , Fig. 1, wherein the parts are shown in their suspended positions for use, and Fig. 3 is a section on line y, y , Fig. 1.

Referring particularly to the drawing, my 35 improved cord holder preferably comprises a base or bottom member indicated at 10 in which, and preferably centrally, an aperture 11 is provided. I also employ a series of side members, each of which is a pair or comprises two parts indicated at 12 and 13 respectively. The parts of each pair are similar in outline,—being trapezoidal,—the opposite edges of which are respectively parallel and converging; the short parallel edges being of the same length as the edge of one of the sides of the base member 10. The lower edge of each of the parts 12 is hinged to an edge of the base member 10 as indicated at 45 14 and the long parallel edges of the parts 12 50 13 of each of the said pairs of side members are hinged together as indicated at 15. The short parallel edges of the parts 13 of each of the pairs of said members and at the corners thereof formed by meeting the adjacent converging edges are provided with holes 16, and 55 hooks 17 are passed through the holes 16 in

the adjacent corners of the parts 13 of each of the said pairs of side members and to each of the hooks 17 a chain 18 is attached, the opposite ends of the chains 18 being secured 60 to a hook 19 common to them all, from which the cord holder is suspended.

It will now be apparent that the hereinbefore described article may be readily collapsed or opened out to admit the ball of 65 cord shown in dotted lines 20 Fig. 2, or other material to be unwound therein and drawn therefrom and also that the device is collapsible, (see Fig. 3) thereby taking up comparatively small space and so being convenient 70 and effecting a saving in the expense of packing and shipping.

While I have shown in the drawing a cord holder which is pentagonal in outline, I do not limit myself to the article taking this 75 form, because manifestly it may be made of any number of sides more than two without departing from the nature and spirit of my invention, and furthermore while the article is preferably made of sheet metal for the particular purposes hereinbefore named, it may be made of other material employed for other obvious purposes to equal advantage.

I claim as my invention:

1. A collapsible cord holder comprising a 85 base, side members arranged in pairs, the parts of each pair being hinged together and one part of each pair being hinged to the said base, and means for suspending the holder.

2. A collapsible cord holder comprising a 90 base having an aperture therein, series of side members arranged in pairs and corresponding in number with the edges of the base, the parts of each pair of side members being hinged together and one part of each 95 pair being hinged to the said base, and means for suspending the holder from the said side members.

3. A collapsible cord holder comprising a 100 base having a central aperture therein, series of side members arranged in pairs and corresponding in number to the edges of the said base, the parts of each pair being similar in outline and having opposite parallel and converging sides respectively, hinges connecting 105 the longer parallel sides of the parts of each of the said side members, hinges connecting the shorter parallel edge of one part of each of the side members to an edge of the said base, and means for suspending the holder 110 from the said side members.

4. A collapsible cord holder comprising a

base having a central aperture therein, series of side members arranged in pairs and corresponding in number to the edges of the base, the parts of each of the said side members being trapezoidal and of the same size and having opposite parallel and converging sides, a hinge connecting the longer parallel sides of the parts of each of the said bars, a hinge connecting the shorter parallel side of the lower part of each of the said sides to an edge of the base, and chains connected to the short edges of the upper part of each of the said pairs of side members whereby the holder may be suspended.

5. A collapsible holder for a ball of cord or 15 similar article, comprising an apertured base and series of members in parts arranged around said base, the parts of each of the said members being hinged together and one of the said parts of each member being 20 hinged to the base, the whole forming an inclosing shell for the article held therein and means for suspending the same.

Signed by me this 28th day of April 1908.
MORITZ MAYER.
